Specification for Design.

Patented Dec. 21, 1915.

Application filed July 13, 1915. Serial No. 39,686. Term of patent 14 years.

To all whom it may concern:

Be it known that I, CLEMENT L. HUGHES, citizen of the United States, residing at Lewistown, in the county of Fulton and State of Illinois, have invented a certain new, original, and ornamental Design for a Vending-Machine Casing, of which the following is a specification, reference being had to the accompanying drawing, forming part thereof.

Figure 1 shows my new design of a vending machine casing in perspective; and, Fig. 2 is an elevation of the same.

I claim:—

The ornamental design for a vending machine casing as shown.

In testimony whereof I affix my signature, in presence of two witnesses.

CLEMENT L. HUGHES.
